UNITED STATES PATENT OFFICE.

HANS WIEDERKEHR, OF ZURICH, SWITZERLAND, ASSIGNOR TO FIRM SCHWEIZERISCHE LOKOMOTIV- & MASCHINENFABRIK OF WINTERTHUR, SWITZERLAND.

INTERNAL-COMBUSTION ENGINE.

Application filed October 2, 1922. Serial No. 591,953.

To all whom it may concern:

Be it known that I, HANS WIEDERKEHR, a citizen of the Republic of Switzerland, residing at Zurich, Switzerland, have invented certain new and useful Improvements 5 in Internal-Combustion Engines, of which the following is a specification, reference being had therein to the accompanying drawing.

The invention relates to improvements in 10 internal combustion engines and particularly to a fuel pump for such engines working with direct injection of the fuel. In contradistinction to Diesel-engines with engines of the above type the fuel is not injected into 15 the cylinder by means of compressed air, but by means of a fuel pump and a nozzle. A complete atomizing of the fuel is very essential for attaining a good combustion, the complete atomizing requires a fuel jet of 20 uniform strength during the whole period of injection and the start and the termination 25 of the injection should take place almost instantaneously in order to prevent the formation of drops at the opening of the nozzle. These requirements can be attained 30 for instance by the provision of a mechanically operated valve inserted in the fuel conduit in front of the nozzle, the fuel being then always under pressure in front of the 35 valve.

According to the present invention the same end is obtained by a fuel pump by 40 means of which the fuel is directly injected into the combustion space through the open nozzle and which pump is so designed that the compression period is limited to the period in which the pump piston has its greatest speed. This is attained by determining the beginning and the termination of 45 the compression period at the closing and the opening the suction valve in suitable moments; the control of the suction valve being derived from the movement of the pump piston.

It is known with Diesel-engines to regulate the quantity delivered by the fuel pump by controlling the suction valve, but the termination of the discharge is effected 50 when the pump piston is in one of its dead centre positions, so that the discharge ceases gradually the manner in which the fuel is supplied being of no importance with Diesel-engines.

A constructional example of the subject 55 matter of the invention is shown on the ac-

companying drawing, showing a vertical section through the fuel pump. The extreme positions of the various levers being diagrammatically indicated by dotted lines.

The piston C of the pump is reciprocated 60 by the eccentric E, the stroke of the piston is indicated by H. The fuel is supplied by the pipe Z; S denotes the controllably arranged suction valve having a portion extending in the downward direction, D is the 65 automatic pressure valve and L denotes a pipe leading to the fuel nozzle. K and M are controlling levers operated by the piston C. The fulcrums X and Y of the levers K and M respectively are formed by the pins 70 of small cranks; the axles of the cranks pass through the casing of the pump and carry outside the casing the levers N and O respectively, which levers can be turned by the link R connected to the sleeve of a 75 governor G.

In the lower dead center position of the piston C, at which point the compression stroke begins when the eccentric is rotated in the direction of the arrow P, the suction 80 valve S rests on the one end of the upper lever K and in this position the valve body is lifted above its seat to a small extent so that fuel displaced by the piston C moving in the upward direction can escape through 85 the open suction valve. Upon the further upward movement of the piston G the suction valve S is no longer supported by the lever K and is pressed down on its seat by 90 the action of the spring T, and fuel is now forced through the pressure valve into the nozzle. The compression period starts when the pump piston moves at its greatest speed and lasts during the angular turn of the eccentric indicated by the angle W. When 95 the eccentric has been turned through said angle and when it is in the position F the compression period is interrupted as the lower lever M abuts against the extension S' of the suction valve S and lifts the latter. 100

The fuel which is further displaced by the piston C escapes through the open suction valve.

By means of an adjustment of the lever N the fulcrum of the upper lever K is raised 105 or lowered and thereby the suction valve will sooner or later be pressed on its seat, i. e., the beginning of the compression period will occur sooner or later. When the lever O is adjusted by a turning movement in the 110

clockwise direction, the fulcrum Y of the lower lever M is raised, the suction valve will be lifted off its seat earlier whereby the termination of the compression period is caused, the angle W during which the compression period takes place is thereby decreased. The adjustment of the levers N and O may be carried out simultaneously or the levers may be singly adjusted either by hand or by a governor.

I claim:

1. In a fuel pump for internal combustion engines, the combination of a cylinder, its plunger, a fuel supply a valve controlling the connection between said fuel supply and said cylinder, a lever operating in unison with said plunger and controlling said valve to determine the beginning of the pressure stroke, a second lever operating in unison with said plunger and controlling said valve to determine the end of the pressure stroke and means adapted to alter the stroke of said levers so that the beginning as well as the end of the pressure stroke is altered.
2. In a fuel pump for internal combustion engines, the combination of a cylinder, its plunger, a fuel supply, a valve controlling the connection between said fuel sup-

ply and said cylinder, a lever pivoted on an eccentric fulcrum and operating in unison with said plunger and controlling said valve to determine the beginning of the pressure stroke, a second lever pivoted on an eccentric fulcrum and operating in unison with said plunger and controlling said valve to determine the end of the pressure stroke, and means to alter the eccentricities of said fulcrums so that the beginning as well as the end of the pressure stroke is altered.

3. In a fuel pump for internal combustion engines, the combination of a cylinder, its plunger, a fuel supply, a valve controlling the connection between said fuel supply and said cylinder, a lever pivoted on an eccentric fulcrum and operating in unison with said plunger and controlling said valve to determine the beginning of the pressure stroke, a second lever pivoted on an eccentric fulcrum and operating in unison with said plunger and controlling said valve to determine the end of the pressure stroke, and means operatively connected to a governor to alter the eccentricities of the fulcrums so that the beginning as well as the end of the pressure stroke is altered.

In testimony whereof I affix my signature.
HANS WIEDERKEHR.
